UNITED STATES PATENT OFFICE.

JAMES ALEXANDER SORRELLS, OF GAINESVILLE, GEORGIA.

TAPE-SELVAGE STOP-MOTION STAND.

1,416,133.

Specification of Letters Patent. Patented May 16, 1922.

Application filed January 10, 1922. Serial No. 528,196.

To all whom it may concern:

Be it known that I, JAMES ALEXANDER SORRELLS, a citizen of the United States, residing at Gainesville, in the county of Hall 5 and State of Georgia, have invented a new and useful Tape-Selvage Stop-Motion Stand, of which the following is a specification.

This invention aims to provide a simple stand adapted to hold the drop wires through 10 the tape threads run, in weaving tape selvage cloth. Hitherto, this portion of a loom has included so much mechanism and has been so complicated, as to be impractical, or at least undesirable, and the principal object 15 of this invention is to simplify devices of the kind above alluded to.

It is within the province of the disclosure to improve generally and to enhance the utility of devices of that type to which the 20 invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from the 30 spirit of the invention.

In the drawings:—

Figure 1 shows in side elevation, a device constructed in accordance with the invention, mounted on a loom; Figure 2 is a top 35 plan; Figure 3 is a section on the line 3—3 of Figure 1; Figure 4 is a section on the line 4—4 of Figure 1; and Figure 5 is a perspective view showing a portion of the stand.

The numeral 1 marks a loom girt, and on 40 the loom girt is mounted the stand 2 forming the subject matter of this application, the stand comprising a pedestal 3 having a slot 4 in its lower end, the slot defining arms 5 between which the loom girt 1 is located. 45 At its upper end, the pedestal has a head 8, a seat 9 being formed in the upper edge of

the head 8 transversely thereof. The arms 5 have enlargements 6, accommodating a securing element 7, such as a screw, whereby the pedestal 3 may be held on the loom girt 50 1. Securing members 10 which may be screws are mounted in one end of the head 8 of the pedestal 3 and extend across the seat 9. The stand includes a bracket, denoted generally by the numeral 11, and comprising a shank 12 and an arm 14 disposed at right angles thereto, the shank 12 being secured to the arm 14, as indicated at 15 intermediate the ends of the arm, the arm terminating in oppositely inclined fingers 16 60 and 17. The free end of the shank 12 is received in the seat 9 of the head 8 and has openings 18 adapted to receive the securing members 10. The drop wires 19, of which there may be any desired number are carried 65 by the shank 12.

The device forming the subject matter of this application is simple in construction and will be found well adapted for the purposes set forth in the opening portion of this 70 specification.

Having thus described the invention, what is claimed is:—

1. A device of the class described, comprising a pedestal, and a bracket including a 75 shank and a head disposed transversely of the shank, the shank being assembled with the pedestal and constituting a drop wire carrier.

2. In a device of the class described, a 80 stand comprising a pedestal having a seat, the pedestal being bifurcated to form arms; and a bracket including a shank received in the seat, and a head on the shank and disposed transversely thereof.

In testimony that I claim the foregoing as my own, I have hereto affixed my signature in the presence of two witnesses.

JAMES ALEXANDER SORRELLS.

Witnesses:

R. G. McCONNELL,
R. G. HARPER.
